UNITED STATES PATENT OFFICE.

CHARLES M. BUMP, OF BAY CITY, MICHIGAN.

MASSAGING-MACHINE.

1,134,181.

Specification of Letters Patent.

Patented Apr. 6, 1915.

Application filed September 18, 1914. Serial No. 862,283.

To all whom it may concern:

Be it known that I, CHARLES M. BUMP, a citizen of the United States of America, residing at Bay City, in the county of Bay and State of Michigan, have invented certain new and useful Improvements in Massaging-Machines; and I do hereby declare the following to be a full, clear, and exact description of the invention, such as will enable others skilled in the art to which it app pertains to make and use the same.

This invention relates to massaging machines and is of the type adapted for the massaging of the back adjacent the spinal column in a manner similar to the osteopathic treatment of the spine.

It is the object and purpose of my invention to provide a machine of this kind by which one can give massaging treatments of this character to himself without the necessity of going to a skilled practitioner.

It is a further object of the invention to combine with the structure a means for giving electrical treatments in connection with the massaging treatments.

Other objects and purposes will be apparent as the description progresses, and as understanding is had of the construction shown in the accompanying drawings in which:

Figure 1 is a perspective view of my massaging machine. Fig. 2 is an end elevation of an element of the machine. Fig. 3 is a side view of said element with parts shown in section. Fig. 4 indicates in dotted outline the normal position of the parts of the machine and in full lines the extreme position occupied by said parts in the course of a treatment therewith. Fig. 5 is a detail of the support for said machine; and Fig. 6 illustrates, diagrammatically, the method or manner in which treatments with said machine are taken.

Like reference characters refer to like parts throughout the several views of the drawing.

In the construction of my massaging machine, a base 1, preferably of metal, is provided and at each end thereof are secured upright sheet metal sections 2 having bent therefrom the angular extensions 3 which bear against and are secured at the ends of the base 1. At the upper corners of each of the sections 2 are pivoted the metal segments 4 which extend toward each other and which at their adjacent ends are provided with

gear teeth 5 meshing one with the other as shown. Adjacent a lower corner of each segment 4 is pivotally attached the upwardly extending sheet metal members 6 which cross each other as shown and which are pivotally connected together, a rod 7 extending between and furnishing the pivotal connection for each pair of the members 6. Rods 8 are also provided extending between the lower ends of members 6 and passing through the segments 4, the ends thereof being received in the slots 9 cut in sections 2.

At their upper ends each of the members 6 are provided with inturned horizontal portions 10 to which are attached the jaws 11, the outer edges of which are provided with corrugated formations 12 simulating the knuckles of a person's hand. There are two of these jaws 11 as shown carried by and between a pair of the spaced apart members 6. Rods 13 extend between the members 6 as shown, passing through openings therein, the pair of rods 13 being spaced apart and having interposed therebetween coil springs 14 under tension, the normal tendency of which is to draw the rods and consequently the jaws 11 closer together.

A link 15 is pivotally attached on the inner side of each of the members 6 as shown in Fig. 1, and at their upper ends the links of a pair of members 6 are brought together and pivotally secured adjacent the upper end of a member 16 which is positioned substantially upright and which at its lower end is slotted at 17 passing over the rod 7. There are two of these members 16 which are spaced apart and lie adjacent the spaced apart pairs of members 6 and at their upper ends they are secured to the downturned ends of a cross bar 18, which carries on the upper face thereof, a bar 19 consisting of a core formed preferably of wood and covered with a fabric covering 20, preferably of felt. The wood center or core is bored for a portion of its length for the reception of a wire 21 which may be carried to any convenient place for connection with a source of electric energy.

The machine as thus constructed is adapted to be supported with the base 1 in a vertical plane as indicated in Fig. 6, a bracket 22 being attached to any suitable support such as a wall or the like and carrying a depending rod 23 which passes through openings in the sections 2 of the machine as shown in Fig. 1 and which carries the collar

24 adjustable along the length of rod 23 and adapted to be fixed in place at any point along the length thereof by the set screw 25. The base 1 on the underside thereof is provided with a plurality of members 26 preferably of rubber, or at least rubber covered, which may bear against the wall as shown in Fig. 6 without danger of marring or defacing it.

10 In the operation of the machine it is supported with the base in a vertical plane as indicated in Fig. 6 and the collar 24 adjusted to any desired position on the rod 23. The person taking the treatment positions 15 himself before the machine with the corrugated sections 12 at either side of the spinal column, and then by pressing backward against the machine the tension of the 20 springs 14 may be overcome and the jaws which terminate in the corrugated portions 12 may be forced apart, this operation being indicated in Fig. 4, where the dotted lines show the initial position at the beginning 25 of the operation and full lines the final position. It will be apparent that in the course of this operation the corrugated portions 12 corresponding to the knuckles of a person's hand will press against and massage portions of the back adjacent the spinal column 30 beginning immediately adjacent the spinal column and working outwardly therefrom, in a manner similar to the osteopathic treatment as given by practitioners who use the knuckles of the closed hand to give said treatment. It will also be apparent that at 35 the beginning of said operation the member 19 will not be in contact with the back but as the jaws are opened a short distance it will come in contact therewith and will be 40 in contact during the latter part of the operation as shown in Fig. 4, said member 19 being carried to the rear with the opening of the jaws. It will be noted in this connection that, if desired, an electrical treatment 45 may be taken in connection with the massaging treatment. The wire 21 may be connected with any suitable source of electric current such as an electric battery and the other wire of the battery may be held in the 50 hand of the person operated upon whereupon as the back comes in contact with the member 19, the circuit will be completed, it being designed in such case that the covering 20 of member 19 shall be moistened to permit the ready conduction of the electric current.

The operation as heretofore described may be repeated as many times as desired, and the machine may be raised and lowered 60 along the rod 23 so that any desired portion or portions of the back may be subjected to the massaging treatment. It is designed that the springs 14 carried by the rods 13 adjacent the ends thereof may be 65 readily removed, this being of advantage

especially when the treatment is taken in direct contact with the flesh without any protective covering between the corrugated portions 12 and the flesh. This will be practically necessary whenever an electrical treatment is also had. If however, the electrical treatment is not desired, the massaging treatment may be taken even with the body 70 partially clothed in which case the stronger tension exerted by the additional springs 14 75 will not serve to injure the person treated the same as if the corrugated parts 12 were in direct contact with the flesh. Also when the body is partially clothed, the member 19 will serve to keep the clothing against the 80 body so that it will not be caught between the jaws 11 and at all times in the operation of the machine, the member 19 serves to limit the approach of the jaws toward each other, said jaws not being permitted to come 85 close together which would be, in many cases, undesirable.

Various changes in form, proportions, and minor details of construction may be had without departing from my invention which 90 is defined in the appended claims and which covers all modifications in structure falling within the scope thereof.

I claim:

1. In a device of the character described, 95 a base, pivotally mounted jaws, means whereby said jaws may be made to simultaneously move away from each other and toward the base, and means normally tending to draw said jaws together and away from 100 the base.

2. In a device of the character described, a base, segments pivotally mounted thereon extending toward each other and having 105 interengaging teeth, jaws pivotally mounted on the segments and means normally tending to draw the jaws toward each other.

3. In a device of the character described, a base, pivotally mounted jaws, means 110 whereby said jaws may be made to simultaneously move away from each other and toward the base, means normally tending to draw said jaws together and away from the base, and means limiting the movement of 115 the jaws toward each other.

4. In a device of the character described, a base, pivotally mounted jaws, links attached one adjacent either end of each jaw, a bar normally located between the jaws, and pivotal connections between said bar 120 and the links.

5. In a device of the character described, a base, segments at each end of the base pivotally mounted thereon and extending 125 toward each other, teeth formed on the segments the teeth of the segments adjacent each end of the base being interengaged, members pivotally mounted adjacent each end of the base, one to each segment, said members being crossed and pivotally con- 130

nected together in pairs, and jaws connecting the said members, substantially as described.

6. In a device of the character described, 5 a base, spaced apart metal sections projecting from the base, segments pivotally mounted adjacent the corners of the sections, extending toward each other and having interengaging teeth, members pivotally 10 connected to the segments, said members crossing adjacent each section, a bar extending between said members and forming a pivotal connection for the members in pairs, jaws connecting said members, rods extending 15 between the members substantially parallel to the jaws, and springs interposed between the rods tending to draw said rods toward each other.

7. In a device of the character described, 20 a base, spaced apart sections extending at right angles thereto, segments pivoted to the sections, members pivotally connected to the segments and crossing in pairs, a rod interposed between the pairs of members furnishing 25 a pivotal connection thereto at the cross-

ing thereof, jaws connecting the spaced apart members, means tending to draw the jaws toward each other, a bar lying between the jaws, link connections between said bar and the said members, and slotted members 30 connected to said bar extending to and receiving the said rod, substantially as described.

8. In a device of the character described, 35 a support, jaws pivotally mounted and movable toward and away from the support simultaneously with movement of the jaws away from and toward each other, a bar located between the jaws, and connection between the bar and jaws whereby it is moved 40 toward and away from the support simultaneously with similar movements of the jaws toward and away from said support.

In testimony whereof I affix my signature in presence of two witnesses.

CHARLES M. BUMP.
